IMPRESSION FRAME FOR MAKING TILE-SIMULATING IMPRESSIONS IN WET CEMENT

Gregorio B. Cardenas, 17412 Hood Court,
Fountain Valley, Calif. 92708

Filed June 5, 1975, Ser. No. 584,023

Term of patent 14 years

Int. Cl. D8—05

U.S. Cl. D8—45

Fig-1

Fig-2

FIG. 3

FIG. 4

FIG. 1 is a side elevation view of an impression frame for making tile-simulating impressions in wet cement, showing my new design, as viewed from below FIG. 2;

FIG. 2 is a top plan view thereof;

FIG. 3 is an end elevation view thereof, viewed from the right of FIG. 1, the opposite end being substantially the mirror image thereof; and

FIG. 4 is a bottom view thereof.

I claim:

The ornamental design for an impression frame for making tile-simulating impressions in wet cement, as shown and described.
